UNITED STATES PATENT OFFICE

111,122

DESIGN FOR A CURLING COMB

Daniel D. Whyte, New York, N. Y., assignor to
Injection Moulding Corp., New York, N. Y., a
corporation of New York

Application February 3, 1938, Serial No. 74,817

Term of patent 3½ years

To all whom it may concern:

Be it known that I, Daniel Whyte, a citizen of the United States, with residence in the county of Kings, city and State of New York, and post-office address at No. 113 Fourth Avenue, county of New York, city and State of New York, have invented a new, original, and ornamental Design for Curling Comb, of which the following is a specification, reference being had to the accompanying drawing, forming part thereof, in which

Figure 1 is a front elevational view of a curling comb showing my new design and;
Figure 2 is a top plan view thereof.

The characteristic features of my design reside in a curling comb having curling members of the contour, arrangement and proportions shown.

I claim:

The ornamental design for a curling comb, as shown and described.

DANIEL D. WHYTE.
